UNITED STATES PATENT OFFICE.

JAMES A. DODD, OF LEXINGTON, KENTUCKY.

GATE.

Application filed September 1, 1925. Serial No. 53,361.

This invention relates to an improved gate and seeks, among other objects, to provide a novel gate structure wherein the gate may be opened by a vehicle approaching the gate, 5 and, after the vehicle has passed through, again closed by the vehicle.

The invention seeks, as a further object, to provide a novel mounting for the gate whereby the gate may be caused to swing 10 to open or closed position.

And the invention seeks, as a still further object, to provide an improved and simple operating mechanism for the gate.

Other objects of the invention not above 15 specifically mentioned will appear as the description proceeds.

In the accompanying drawings:

Figure 1 is a plan view of my improved gate.

20 Figure 2 is a transverse vertical sectional view on the line 2—2 of Figure 1, looking in the direction indicated by the arrows.

Figure 3 is a detail perspective view showing the crank shaft which swingingly supports the gate.

25 Figure 4 is a detail perspective view particularly showing the latch.

Referring now more particularly to the drawings, wherein I have illustrated the preferred embodiment of the invention, the numerals 10 and 11 indicate suitable gate posts at opposite sides of a roadway. Fixed to the post 10 are vertically alined brackets 12, which may be formed of eye bolts or 30 screw eyes and journaled through the eyes of said brackets is a crank shaft 13. Extending from the shaft near its upper end is a long crank 14, and extending from the shaft near its lower end is a short crank 15, the shaft and said cranks being an integral structure. The cranks are disposed in parallel relation to extend laterally from the shaft and at their outer ends, are provided with upstanding trunnions 17. As 35 will be observed, the cranks rest on the brackets 12 for supporting the shaft 13 against downward movement.

40 The gate is indicated at 18. This gate preferably comprises a rigid metal frame 19, and fixed to one end of the frame near the upper edge of the gate is a short hinge bracket 20 apertured to fit over the trunnion 17 of the long crank 14, while near the lower edge of the gate is provided a 45 long hinge bracket 21 apertured to fit over the trunnion 17 of the short crank 15. The

gate is thus mounted to swing upon said cranks and, as brought out in Figure 2, the inner end of the gate lies in parallel relation to the shaft 13. Fixed to the post 60 11 is a keeper 22, and fixed to the frame of the gate at the outer end thereof is a channel-shaped latch supporting plate 23 in which is pivoted a latch 24 engageable with the keeper for securing the gate closed. 65 As shown in detail in Figure 4, the lower side flange of the plate 23 may be bent up at its forward end to provide a lug 25 for supporting the free end portion of the latch against undesired downward movement and maintaining the latch in a substantially horizontal position to cooperate with the keeper. 70

Countersunk in the roadway to lie flush therewith at one side of the gate is a transversely disposed sill 26, and similarly arranged at the opposite side of the gate is a like sill 27. These sills are preferably of cement, although other suitable material may be employed. Mounted upon the sill 26 is a crank rod 28 having cranks 29 and 30 disposed at substantially a right angle to each other, and mounted upon the sill 27 is a crank rod 31 having similarly disposed cranks 32 and 33. Journaling the rods are pairs of bearings 34 which are disposed close 75 at opposite sides of the cranks of the rods and are bolted or otherwise secured to the sills 26 and 27. Fixed to corresponding ends of the rods 28 and 31 are crank arms 35, and fixed to the lower end of the crank shaft 13 80 of the gate is a crank arm 36. As shown in detail in Figure 3, the shaft is provided near its lower end with a squared portion 37 to receive the arm 36, and screwed on the lower end of said shaft is a nut 38 detachably securing the arm in position. Connecting the arms 35 of the crank rods with the crank arm 36 are rods 39 having laterally turned ends 40 engaging through said crank arms and secured by suitable pins. 85

90 As shown in Figure 1, the cranks 29, 30, 32 and 33 of the rods 28 and 31 are so arranged that when the gate is closed, the cranks 29 and 33 upstand from the roadway while the cranks 30 and 32 lie parallel to the roadway close thereto. Accordingly, 95 a vehicle moving along a roadway and approaching the gate from one direction, may be caused to travel over the crank 29 of the rod 28 with the result that this crank will be swung downwardly to the dotted line 100 position shown. As will be understood from 110

the foregoing description, such movement of the crank 29 will cause the crank shaft 13 of the gate to be rotated to the left and, as will be appreciated, the gate 18 will, due to the inequality in the length of the cranks 14 and 15 of the shaft 13, be tilted and thus caused to swing open in the direction of the approaching vehicle. For this reason, the crank rod 28 is, as shown in Figure 1, located further from the gate than is the rod 31. Tilting of the gate, by the rotation of the shaft 13, will, of course, lift the free end of the gate so that the latch 24 will be released by the keeper 22, when the gate will gravitate to open position and, as shown in Figure 1, a suitable stop 41 is preferably provided at one side of the roadway for limiting the gate in its opening movement. As the vehicle continues along the roadway, said vehicle may then be caused to travel over the crank 32 of the rod 31, when the crank shaft 13 will be rotated to the right, thus causing the gate to close. As the gate approaches closed position, the latch 24 will, of course, ride over the keeper 22 into engagement therewith for again securing the gate closed. As will be perceived, when the crank 29 is swung down, incident to the approach of the vehicle, the crank 32 will be swung up to active position so that the wheels of the vehicle may subsequently be caused to travel over the latter crank for closing the gate. Similarly, a vehicle moving along the roadway and approaching the gate from a direction opposite to that pre-

ously referred to may first be caused to travel over the crank 33 of the shaft 31 for opening the gate, and may then be caused to travel over crank 30 of the rod 28 for closing the gate. I thus provide a particularly simple and efficient structure for the purpose set forth and a gate well adapted for general use.

Having thus described the invention, what I claim is:

A structure of the character described comprising a support, bearings carried by said support in vertical spaced relation to each other, a shaft rotatable in said bearings, upper and lower arms extending from said shaft and provided with upstanding trunnions, the upper arm being of greater length than the lower arm, a gate, upper and lower brackets extending from one end of said gate and rotatably fitted upon the trunnions of said arms, the upper bracket being of less length than the lower bracket, said shaft having its lower portion reduced and noncircular in cross section and terminating in a threaded stem, a crank arm snugly fitted upon the noncircular portion of said shaft, a securing nut screwed upon said stem to hold said crank arm in place, and actuating means connected with said crank arm and adapted to move the same to rotate said shaft and impart swinging movement to said gate.

In testimony whereof I affix my signature.

JAMES A. DODD. [L. S.]
